UNITED STATES PATENT OFFICE.

JOHN H. DALE, OF NEW YORK, N. Y.

CLUSTER-SOCKET.

No. 826,152.

Specification of Letters Patent.

Patented July 17, 1906.

Application filed May 25, 1905. Serial No. 262,170.

To all whom it may concern:

Be it known that I, JOHN H. DALE, a citizen of the United States, residing at the city of New York, in the borough of Manhattan and State of New York, have invented certain new and useful Improvements in Cluster-Sockets, of which the following is a full, clear, and exact description.

My invention relates to cluster-sockets for incandescent lamps, and comprises means for facilitating the assembling of a comparatively large number of shell lamp-contacts together with the other lamp-contacts in a small inclosing casing, so that the shell-contacts will extend through perforations in the casing. When a small number of lamp-contacts is used, their insertion in the casing without dismantling them from their base involves no special difficulties, but when the number of lamp-contacts is large some special construction becomes necessary to use them in connection with a small outer casing. My invention meets this latter requirement by the use of pivoted contacts, thus allowing the contacts to be turned to facilitate their insertion in the casing. It also involves a new and improved supporting means for the shell-contacts, so that a larger number can be used in a given space than has heretofore been customary, at the same time allowing them to be inserted without any dismantling from their common block.

My invention is not limited to a cluster-socket, but some of its features may be applied to incandescent lamps broadly.

The invention will be readily understood from the following description, taken in connection with the accompanying drawings, wherein like reference characters refer to the same parts.

Figure 1 represents a vertical central section of a cluster lamp-socket. Fig. 2 is also a section of a portion of the interior mechanism of said socket and shows the manner in which the shell-contacts may be manipulated. Fig. 3 is a view looking into the casing 4 after it has been removed from the base 2.

Referring to Fig. 1, 2 represents a base supported by and threaded upon the lower end of the supporting-pipe 1, through which the wires leading to the socket pass. Attached to the base 2 by means of pins or screws 3, engaging slots in said base, is the perforated shell 4, through the perforations

of which the incandescent lamps extend into their sockets. Within this shell 4 is the insulating-block 5 with a flat bottom surface and with a central hub 6, extending upwardly from its upper surface, said hub being recessed at 7. Passing through this portion 6 is the screw 8, which engages the lower contact-plate 10, held against the lower surface of the base 5 by screws passing through the base, said screw 8 having secured between its head and the washer 9 one of the leading-in wires. 65 From the plate 10 contact-lugs 11 extend upwardly, each forming the center contact of a lamp-socket. On the upper side of block 5 is the metallic ring 12, flanged at its base 13 and secured to the block 5 by means of screws 70 passing through the block. This ring replaces the usual plate-contact. The top portion of ring 12 is flanged inwardly, as at 14. The said ring is slotted at proper intervals to allow for the insertion of links 15, which are 75 held to the ring by a wire 16, passing through perforations at the inner ends of said links and extending under the flange 14. In this manner the links 15 are pivoted to the metallic contact-ring 12. The outer ends of 80 these links are pivoted to shell-contacts 18, two links being attached to each shell by means of pins or screws 17. The links 15 converge as they extend inwardly from the shell-contacts, so as to allow the maximum 85 number of shell-contacts to be placed in the casing. From this construction it will be noted that the shell-contacts 18 are doubly pivoted to the metallic ring 12, so that they may be turned upwardly and also drawn inwardly to a considerable extent, as is clearly shown in Fig. 2. Between the shell-contacts 18 and the exterior casing 4 are the insulating-bushings 19, which are threaded internally to engage the exterior threads of the 90 shell-contacts. The bushings are also flanged so as to neatly abut against the exterior shell 4. As is stated above, screw 8 comprises one terminal of the cluster-socket and the other terminal 20 is attached to one or 100 more of the links 15, and in this manner current is conducted to all the links, the ring 12, and the shell-contacts.

When it is desired to insert block 5 and the attached lamp-sockets in the casing 4, by 105 properly turning and drawing inwardly one or more of the shell-contacts 18 on its pivots the block 5 and all the sockets can be readily

- inserted without any dismantling of the lamp-contacts from their block. By a similar manipulation the block and its attached sockets can be readily removed from the casing, if such removal becomes desirable.
- It is to be understood that various modifications may be made in the construction of such a cluster-socket and yet fall within the spirit and scope of my invention.
10. I have shown my invention as applied to a cluster-socket for six lamps; but it is obvious that it may be applied to a socket employing any number of lamps.
- What I claim as my invention, and desire 15 to secure by Letters Patent of the United States, is—
1. An incandescent-lamp socket comprising, a shell-contact, and two converging supporting-arms flexibly attached to said contact.
  2. An incandescent-lamp socket comprising, a shell-contact, and two converging supporting-arms pivoted to said contact.
  3. An incandescent-lamp socket comprising, a block, a plurality of converging supporting-arms pivoted to said block, and a lamp-contact secured to said arms.
  4. A cluster incandescent-lamp socket comprising, a plurality of lamp-contacts, and a plurality of converging arms pivoted to each of said lamp-contacts.
  5. A cluster incandescent-lamp socket comprising, a block, a plurality of lamp-contacts, and a plurality of converging links pivoted to each lamp-contact, all of said links being pivoted to said block.
  6. An incandescent-lamp socket, comprising a casing with an opening therethrough, a link, and a lamp-contact secured to said link and adapted to extend through said opening.
  7. An incandescent-lamp socket comprising, a link and a lamp-contact pivoted to said link.
  8. An incandescent-lamp socket, comprising a casing with an opening therethrough, a link and a lamp-contact pivoted to said link and adapted to extend through said opening.
  9. A cluster incandescent-lamp socket, comprising a block, a plurality of links pivoted to said block, and a plurality of lamp-contacts secured to said links.
  10. A cluster incandescent-lamp socket, comprising a casing with a plurality of openings therethrough, a block, a plurality of links pivoted to said block and a plurality of lamp-contacts secured to said links, and adapted to extend through said openings.
  11. A cluster incandescent-lamp socket, comprising a block, a plurality of links pivoted to said block and a plurality of contacts pivoted to said links.
  12. A cluster incandescent-lamp socket, comprising a casing with a plurality of openings therethrough, a block, a plurality of links pivoted to said block and a plurality of contacts pivoted to said links.
  13. A cluster incandescent-lamp socket, comprising a conducting member, a plurality of conducting-links pivoted to said member and a plurality of lamp-contacts secured to said links.
  14. A cluster incandescent-lamp socket, comprising a casing with a plurality of openings therethrough, a conducting member, a plurality of conducting-links pivoted to said member and a plurality of lamp-contacts secured to said links.
  15. A cluster incandescent-lamp socket, comprising a conducting member, a plurality of conducting-links pivoted to said member and a plurality of lamp-contacts pivoted to said links.
  16. A cluster incandescent-lamp socket, comprising a casing with a plurality of openings therethrough, a conducting member, a plurality of conducting-links pivoted to said member, and a plurality of lamp-contacts pivoted to said links and adapted to extend through said openings.
  17. A cluster incandescent-lamp socket, comprising an insulating member, a multiple-contact plate secured to said member, a plurality of links pivoted on said member and a plurality of lamp-contacts pivoted to said links.
  18. A cluster incandescent-lamp socket, comprising a casing with a plurality of openings therethrough, an insulating member, a multiple-contact plate secured to said member, a plurality of links pivoted to said member and a plurality of lamp-contacts pivoted to said links and adapted to extend through said openings.
  19. A cluster incandescent-lamp socket, comprising a insulating member, a multiple-contact secured thereto, a conducting member mounted on said insulating member, a plurality of conducting-links pivoted to said conducting member and a plurality of lamp-contacts pivoted to said links.
  20. A cluster incandescent-lamp socket, comprising a casing with a plurality of openings therethrough, an insulating member, a multiple contact secured thereto, a conducting member mounted on said insulating member, a plurality of conducting-links pivoted to said conducting member and a plurality of lamp-contacts pivoted to said links and adapted to extend through said openings.
  21. In an incandescent-lamp socket, a conducting-ring provided with a flange, a plurality of conducting-links each with a hole therethrough and means passing through said holes and under the flange, to secure the links in place.
  22. The combination of a casing with a plurality of perforations, an insulating-block, a multiple lamp-contact secured to said block,

a plurality of lamp shell-contacts, a conducting member secured to said block, a plurality of conducting-links pivoted to said conducting member, said shell-contacts being pivot-
5 ed to said links for the ready removal and insertion of the shell-contacts through the casting-perforations.

In witness whereof I subscribe my signature in the presence of two witnesses.

JOHN H. DALE.
